US0D1057957S

(12) **United States Design Patent** (10) **Patent No.:** **US D1,057,957 S**
(45) **Date of Patent:** **** Jan. 14, 2025**

(54) **REINFORCEMENT DEVICE**

(71) Applicant: **Maria G. Aboytes**, Palo Alto, CA (US)

(72) Inventor: **Maria G. Aboytes**, Palo Alto, CA (US)

(**) Term: **15 Years**

(21) Appl. No.: **29/800,544**

(22) Filed: **Jul. 21, 2021**

(51) **LOC (15) Cl.** **24-02**

(52) **U.S. Cl.**

USPC **D24/169**

(58) **Field of Classification Search**

USPC D24/107, 133, 143, 144, 155, 167, 169,
D24/231

CPC A61B 17/12022; A61B 17/12113; A61B
17/1214; A61B 17/12145; A61B
17/12172; A61B 2017/00867

(57) **CLAIM**

The ornamental design for the reinforcement device as shown and described.

DESCRIPTION

FIG. 1 is a perspective view of a reinforcement device showing my new design;

FIG. 2 is a bottom view of the reinforcement device;

FIG. 3 is a top view of the reinforcement device;

FIG. 4 is a right side view of the reinforcement device; and,

FIG. 5 is a left side view of the reinforcement device.

1 Claim, 3 Drawing Sheets
